(57) **CLAIM**

The ornamental design for a cooler, as shown and described.

DESCRIPTION

FIG. 1 is a top perspective view of a cooler, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partially enlarged view thereof, taken from FIG. 1;

FIG. 10 is another partially enlarged view thereof, taken from FIG. 1;

FIG. 11 is a partially enlarged view thereof, taken from FIG. 2; and,

FIG. 12 is another partially enlarged view thereof, taken from FIG. 2.

The broken lines in the drawings illustrate the portions of the cooler, which form no part of the claimed design.

The dash-dot-dash broken lines in FIGS. 1-2 and 9-12 are included to show partially enlarged views only and form no part of the claimed design.
